UNITED STATES PATENT OFFICE.

THOMAS S. CATLIN, OF WAVELAND, INDIANA.

JAR-HOLDER.

1,393,010.

Specification of Letters Patent.

Patented Oct. 11, 1921.

Application filed January 13, 1920. Serial No. 351,144.

To all whom it may concern:

Be it known that I, THOMAS S. CATLIN, a citizen of the United States, residing at Waveland, in the county of Montgomery and State of Indiana, have invented certain new and useful Improvements in Jar-Holders; and I do hereby declare the following to be a full, clear, and exact description of the invention, such as will enable others skilled 10 in the art to which it appertains to make and use the same.

This invention relates to improvements in gripping devices, and more particularly to such as are adapted for gripping jars and 15 like containers.

The primary object in view is the provision of means for gripping jars of different standard sizes by means also adapted to grip jars of slightly varying sizes from the 20 standard sizes.

With this and other detail objects in view, the invention comprises certain novel constructions, combinations and arrangements of parts as subsequently specified and 25 claimed.

In the accompanying drawing,—

Figure 1 is a side elevation of a gripping device embodying the features of the present invention, one of the tabs being shown in 30 section.

Fig. 2 is a plan view with the strap sections seen partly in section on the plane indicated by line 2—2 of Fig. 1.

Figs. 3 and 4 are fragmentary elevations 35 of the free end portions of the strap sections.

Fig. 5 is a fragmentary, perspective view of one of the free end portions of the strap sections and tab.

Referring to the drawing by numerals, 1, 1 40 indicate the long arms of operating levers which are pivoted together at 2, and having their short arms 3, 3 extending beyond the pivot and each provided at its outer extremity with an eye 4. Through each eye 4 is 45 looped the respective end of what may be considered the clamping band which consists of two sections, being a section 5 and a section 6. Each section has its end portion looped through its respective eye 4 and folded back upon itself and formed into a tongue 7, which is extended through a slot 8 formed in the respective section of the clamping band. The tongue 7 in each instance is bent down against the inner face of the band. 50 The material of each short arm 3 is stamped 55 for forming its respective eye 4, and the ma-

terial thus stamped out is bent back upon a portion of the remaining materials of the arm to form a bearing piece 9 for the respective terminal loop of the sections 5 and 6. 60 Sections 5 and 6 are thus hinged to the free ends of the short arms 3.

The section 5 is formed with outstanding tabs 10 located intermediate the edges thereof and stamped from the material of section 65 5, each being formed with an elongated tongue 11 at its outer portion and spaced from the band section 5, and forming an open notch between the respective tongue 11 and section 5, and opening toward the hinged 70 end of section 5, that is, toward the free end portion of the band section 6, when the sections 5 and 6 are operably connected. There are as many tabs 10 provided as there are 75 standard sizes of the types of jars to be handled. For example, there are three sizes of the well known Mason jars, being pints, quarts and half-gallons. A tab 10 is provided for each of these standard sizes.

The section 6 has located along its median 80 line a slot 12 of sufficient length to accommodate the tabs 10 provided for the different sizes of jars to be handled. The slot 12 is constructed adjacent the free end of section 6 with separate outer terminals 13 and 85 14 at its outer end portion for accommodating odd sizes or types of jars which would not be considered standard.

To provide for adjustable connection of the clamping sections the terminals 13 and 90 14 are formed a sufficient width to snugly receive the tabs 10 therein, and being located in the line of the notches formed by tongues 11, one of the tabs 10 of section 5 is permitted to overlap and engage the free end portion 95 of section 6.

Beyond the outer terminals of slot 12, the end portion of section 6 is curved outward to form a finger-engaging lip 15.

In operation, when standard jars are being handled, to apply the clamping band to the largest size jar, the section 6 is placed over the section 5 with the terminal 14 in position to engage one of the notches formed by tongues 11 of tabs 10. This can be done 105 by first swinging the sections apart a distance sufficient to allow the sections to be passed about the opposite sides of the body of the jar and then brought to the interlocked position; or the sections may be interlocked and then slid endwise over the jar. 110 When positioned about the jar and inter-

locked, the sections may be caused to grip the jar tightly merely by gripping the handles or operating levers 1. This gripping of the jars may be for the purpose of applying 5 a lid or for removing a lid, or otherwise as occasion may require. The releasing of the jar merely requires the releasing of the handle 1 and either the sliding of the clamping band endwise off the jar or the detaching 10 of the sections by the withdrawal of terminal 14 from engagement with tab 10 and the swinging of the sections apart. The application of the clamp to intermediate or odd size jars will be the same as described 15 except that terminal 13 will be used in place of terminal 14.

What I claim is:—

1. The combination, with hand operating levers, of band sections adapted to form a 20 clamping band and each having one end portion engaging the operating levers, one of said sections being formed intermediate its edges with tabs spaced along the section and the other with a slot to permit interlocking 25 of the sections by engagement of one of the tabs with a terminal of the slot, the slot being of sufficient length to accommodate all of the tabs simultaneously.

2. The combination, with the hand operating 30 levers, band sections adapted to form a clamping band and each having one end portion engaging the operating levers, one of said sections being formed with a tab intermediate its edges and the other with a 35 slot having a plurality of terminals at one

end portion adapted to be engaged by the tab to effect interlocking of the sections while being clamped about jars of different sizes, the tab being movable from one of said terminals to another.

3. The combination, with hand operating levers, of band sections adapted to form a clamping band and each having one end portion engaging the operating levers, one of said sections being formed with a plurality of tabs intermediate its edges spaced apart along the section, and the other section being formed with a slot having a plurality of terminals at one end portion to permit interlocking of the sections for being 50 clamped about jars of varying standard and other variable sizes.

4. The combination, with hand operating levers, of band sections adapted to form a clamping band and each having one end portion engaging the operating levers, one of said sections being formed intermediate its edges with a plurality of tabs spaced apart and the other with a slot having at one end portion a plurality of terminals a greater or less distance from the beginning of the said slot to permit an adjustable interlocking of the sections for being clamped about jars of 55 variable sizes.

In testimony whereof I affix my signature 60 in presence of two witnesses.

THOMAS S. CATLIN.
